US0D1054331S

(12) **United States Design Patent** (10) Patent No.: **US D1,054,331 S**
(45) Date of Patent: ** Dec. 17, 2024

(54) **WHEELCHAIR**

(71) Applicant: **PERMOBIL, INC.**, Lebanon, TN (US)

(72) Inventor: **Douglas Michael Garven, Jr.**, Lebanon, TN (US)

(73) Assignee: **PERMOBIL, INC.**, Lebanon, TN (US)

(**) Term: **15 Years**

(21) Appl. No.: **29/824,703**

(22) Filed: **Jan. 26, 2022**

(51) LOC (14) Cl. **12-12**

(52) U.S. Cl.

USPC **D12/133**

(58) **Field of Classification Search**

USPC D12/128, 131, 133

CPC A61G 2005/048; A61G 5/00-14

See application file for complete search history.

(57) **CLAIM**

The ornamental design for a wheelchair, as shown and described.

DESCRIPTION

FIG. 1 is a perspective view of a wheelchair and associated frame showing the new design;

FIG. 2 is an elevation view of a first side of the wheelchair and associated frame shown in FIG. 1;

FIG. 3 is an elevation view of a second side, opposite the first side of the wheelchair and associated frame shown in FIG. 1;

FIG. 4 is an elevation view of a first end of the wheelchair and associated frame shown in FIG. 1;

FIG. 5 is an elevation view of a second end, opposite the first end of the wheelchair and associated frame shown in FIG. 1;

FIG. 6 is a top view of the wheelchair and associated frame shown in FIG. 1; and,

FIG. 7 is a bottom view of the wheelchair and associated frame shown in FIG. 1.

The portions of the wheelchair in the figures depicted in broken lines form no part of the claimed design.
